(57) **CLAIM**

The ornamental design for an electrical connector terminal, as shown and described.

DESCRIPTION

FIG. 1 is a perspective view of an electrical connector terminal of the design;

FIG. 2 is a front elevational view of the terminal;

FIG. 3 is a rear elevational view of the terminal;

FIG. 4 is a left side elevational view of the terminal;

FIG. 5 is a right side elevational view of the terminal;

FIG. 6 is a top plan view of the terminal; and,

FIG. 7 is a bottom plan view of the terminal.
